UNITED STATES PATENT OFFICE.

WALTER W. CARPENTER, OF CHARLESTON, SOUTH CAROLINA.

PASTE-TUBE CAP.

Application filed March 4, 1922. Serial No. 541,100.

To all whom it may concern:

Be it known that I, WALTER W. CARPENTER, a citizen of the United States, residing at Charleston, in the county of Charleston and State of South Carolina, have invented certain new and useful Improvements in Paste-Tube Caps, of which the following is a specification, reference being had to the accompanying drawings.

10 It is the purpose of the present invention to provide a cap for various paste tubes, such as used for containing tooth paste, cold cream, paints and the like, to permit access to such contents easily and quickly.

15 Heretofore, it is well known that the ordinary caps become distorted, and particularly the threaded neck of the tube, due to the constant removing and reattaching the cap, taking up considerable time, which is 20 very annoying in every respect. Furthermore many users of paste which is contained in tubes remove the caps and place them on a shelf, very often forgetting to replace them on the tubes. Very often the old caps drop 25 into the sink, etc. and also become lost and in this way the paste oozes from the tube and also hardens in the mouth of the tube and therefore creates waste and inconveniences.

30 It is, therefore, another purpose to provide a cap, as an article of manufacture, entirely independent of the tube and capable of being applied to all makes of tubes, generally a threaded neck is used. In other 35 words when opening a tube of tooth paste the cap may be removed and discarded, and the present form of cap screwed to the neck, and in this case, when the occasion requires, the cap proper may be tilted to an open position, by pressing upwardly on the flange 11, thereby permitting the paste to be discharged by depressing the sides of the tube. After the necessary quantity of paste has 40 been taken, the cap proper may be easily closed by pressing the forefinger thereon. After the tube is emptied, the cap may be detached and then applied to a new tube of paste, regardless of the character of paste.

45 While the design and construction at present illustrated and set forth are deemed preferable, it is obvious that as a result of a reduction of the invention to a more practical form for commercial purposes, the invention may be susceptible of changes, and 50 the right to these changes is claimed, pro-

vided they are comprehended within the scope of what is claimed.

The invention comprises further features and combination of parts, as will be hereinafter set forth, shown in the drawings and 55 claimed.

In the drawings:

Figure 1 is a view in perspective of the tube of paste, especially tooth paste, showing the improved cap applied;

Figure 2 is a sectional view on line 2—2 of Figure 1, showing the structure of the cap on an enlarged scale; and

Figure 3 is an enlarged detail perspective view of the cap detached from the tube.

Referring to the drawings, 1 designates a tube, which may contain paste, of any character, such as tooth paste, cold cream, paint or the like. The tube is provided with a threaded neck 2, which is ordinarily provided with the usual threaded cap, which comes with the tube. Threaded to the neck 2 is a band 3, which has a lateral arm 4, the end of which is bifurcated at 5. Formed integral with the arm 4 as at 6 is a spring 7, which is located below the arm 4, and extends in the same general plane with the arm. When the spring extension 7 is not under tension, it assumes a normal parallel position with relation to the arm 4.

Pivoted on a pin 8 and arranged in the bifurcation is an arm 9 carrying a cap or cover 10, constructed integrally therewith. The cap 10 is provided with an annular flange 11, which fits down over the band 3, there being a soft fibre washer or filler or gasket 12 fitted within the cap 10, and adapted to engage the edge of the band 3, to insure a tight fit with the band, so as to prevent any leakage of the paste. The hinged end of the arm, which carries the cap, is provided with a cam which rides upon the spring extension 7. The cam 13 is so disposed relatively to the pivot of the arm carrying the cap, as to hold the cap either 95 closed or open. In fact when the cap is entirely open, the larger portion of the cam is positioned at a point toward the band, in fact between the pivot of the arm and the band, and a flat portion 14 of the pivoted 100 end of the arm is in engagement with the spring extension 7, thereby holding the cap open.

It is obvious that by eliminating the threaded connections between the band 3 and 110

the neck 2 of the tube, and constructing the band integral with the neck, or to construct the lateral arm 4 integral with the neck, it is possible to manufacture the cap as a part 5 of the tube, instead of threading the band 3 on the neck of the ordinary tube.

The invention having been set forth, what is claimed is:—

1. A closure member for receptacles embodying a receptacle having a neck, a collar engaged with said neck, said collar having an extension, a cap adapted to engage one edge of the collar, said cap having an extension adapted to be pivotally connected to 15 the extension of the collar, said extension including means for engagement with the end of the extension of the cap for holding said cap in its raised position.

2. A closure member for receptacles em-

bodying a receptacle having a threaded neck, 20 an internally threaded collar detachably engaged with the neck and projecting above the neck, said collar having an extension, said extension including parallel arms, the lower arm serving as a spring, the upper 25 arm having its end portion bifurcated and provided with a pair of spaced ears, a cap adapted to engage the collar, said cap having an extension, one end of said extension being pivoted between the ears of the upper arm, said pivoted end having an enlargement adapted to be engaged by the spring arm for holding the cap in its raised or lowered position.

In testimony whereof I hereunto affix my 30 signature.

WALTER W. CARPENTER.
